HANS GRUBER, OF MUHLDORF, GERMANY

FUSE FOR MINES OR THE LIKE

Application filed July 28, 1928. Serial No. 296,063, and in Germany January 12, 1927.

The present invention relates to a novel fuse for mines or the like which may be detonated both by a "pull off" or a "shearing" action.

5 Fuses for mines have hitherto been known which cause detonation when a so-called check or safety pin is either drawn out or pressed down. During transport, however, the known fuses require, for the sake of safety, 10 yet another safety device, which usually takes the form of a screw, between the percussion pin and the ignition cap. When now the said safety device is removed to render the fuse capable of operation the latter is 15 no longer sufficiently protected against moisture and may even spoil while in position for this reason. Furthermore in such fuses the percussion pin is at the same time a pressure pin. If, therefore, the fuse is to be actuated 20 by a pressure of any kind, for example, by the weight of a vehicle or the like, the weight of the latter must act directly upon the percussion pin itself to which end the latter projects freely above the fuse housing. Since, 25 however, the percussion pin is comparatively speaking very thin a separate broad pressure plate must be mounted thereon in order to obtain a rather more certain action. A further defect of such fuses resides in the fact that 30 there is always a point liable to leakage where the percussion pin projects out from the fuse housing and it is consequently easily possible for the percussion pin to rust in.

35 The present invention, which has as its object to eliminate these defects, consists in arranging the percussion pin completely inside a fuse head or shearing head serving at the same time as a pressure plate and in securing said pin in the safety position by means of a plurality of pins passing through said percussion pin. As a result the penetration of moisture into the fuse is impossible and the provision of a separate pressure plate on the fuse is no longer essential. There are a plurality of safety actions on the fuse.

Two embodiments of the invention are illustrated by way of example in the accompanying drawings, in which:

50 Fig. 1 is an elevational view of one form of

fuse with a bayonet connection shown in the "unsafe" position.

Fig. 2 a similar view of the fuse with the bayonet connection in the "safe" position and the fuse head screwed out from the fuse body, 55

Fig. 3 is a longitudinal section through the fuse.

Fig. 4 a section through the fuse head,
Fig. 5 a section on the line A—A of Fig. 2,

Fig. 6 a longitudinal section through the percussion pin,

Fig. 7 a section on the line B—B of Fig. 6,
Fig. 8 a longitudinal section through another

er constructional form of fuse in the "safe" position, 65

Fig. 9 an elevational view of the same fuse in the "unsafe" position, and

In the fuse shown in Figs. 1-7 the percus- 70

In the fuse shown in Figs. 1-7 the percussion pin 2 loaded with the pressure of a spring 1 is arranged completely inside the fuse or

1 is arranged completely inside the fuse or shearing head 3 which serves at the same time as a pressure plate, in order to prevent the inward penetration of moisture. The percussion pin 2 is also located inside the fuse body which consists of the two cylindrical portions 4 and 5 screwed together. The outer part 5 of the fuse body carries the supporting means 6 for the fuse cap 7. On operation of the fuse said cap is caused to explode by impact of the point 8 of the percussion pin. The fuse may be screwed to a mine hand-grenade, in this case the like with the aid of the

projectile or the like with the aid of the thread 17 provided at the lower end of the supporting means 6. Three pins 9, 10 and 11 are passed through the percussion pin 2, the first

of which, 9, serves merely as a check or safety pin, the second, 10, as will be further described, the third, 11, is a safety pin, and the fourth, 12, is a safety pin.

scribed, both as a check pin and also as a part of a first bayonet connection and the third, 11, as a part of a second bayonet connection.

11, merely as a part of a second bayonet connection. The check pins 9 and 10 are also

passed through the fuse or shearing head 3 which is also provided with the slots 12, 13 for the longitudinal sections. The check pin

for the bayonet connections. The check pin or shearing pin 10, moreover, passes through the body of the fuse body. It will be ex-

the part 4 of the fuse body. It will be explained below how the pins 9—11 render the 10

fuse "safe" or "unsafe" with the aid of the bayonet connections.

As illustrated in Figs. 2 and 5 the bayonet connections are in the "safe" position. The 5 shearing pin 10 is located in the right hand corner of the bayonet slot 12 and at the same time forms one part of a first bayonet connection. If now the first check pin 9 is withdrawn the percussion pin 2 cannot impact 10 since it is still held by the second check pin 10. Even, however, when the latter has been drawn out or sheared off no actuation of the 15 fuse can take place since there is still a second bayonet connection in the "safe" position, i. e., the third pin 11 forming part of the second bayonet connection passes through the percussion pin 2 parallel to the shearing pin 10. If now the shearing pin 10 is removed then the percussion pin 2 can only move 20 downwardly a short distance by reason of the action of the spring 1 until the pin 11 bears with its projecting ends on the lower surfaces 14 (Figs. 3 and 4) of the bayonet connection 13. Consequently the fuse is in an 25 operated position although not brought to detonation. Further use of the fuse is impossible without previous disassembly of the latter.

The state of affairs is different, however, 30 when the bayonet connections are brought into the "unsafe" position before the withdrawal of the two check pins 9 and 10. This is effected by simple rotation of the fuse head 3 relatively to the fuse body 4. The shearing pin 10 passing through the percussion pin 2 then comes, as illustrated in Fig. 1 into the left hand corner of the bayonet slot 12. Since the friction caused by the spring 1 has also to be overcome on relative rotation of the 35 fuse head 3 unintentional setting of the fuse in the "unsafe" position of its own accord, for example, during transport, is impossible. By said relative rotation the pin 11, which also passes through the percussion pin 2, of the second bayonet connection is rotated so far relatively to the shearing head 3 that it comes over a vertical slot 15 provided, as 40 illustrated in Figs. 4 and 5, in the shearing head. If now the check pin 9 is withdrawn then the fuse is rendered "unsafe" in so far as the percussion pin 2 can, on withdrawal from a distance of the pin 10 or on shearing of the latter by pressure on the fuse head 3, be forced inwardly by the action of the spring 45 1 and cause the fuse cap 7 to explode. The inward movement of the pin 2 is enabled by the vertical slot 15 in which the ends of the pin 11 are adapted to move. As explained 50 above, therefore, striking motion of the percussion pin 2 is not enabled by the withdrawal of one check pin 9, even if the bayonet connection is in the "unsafe" position, so long as the other check pin 10 has not been withdrawn or sheared by loading of the shearing head 3.

As may be clearly seen from Fig. 3 the first pin 9 is so arranged that it holds the percussion pin 2 only and cannot be sheared by loading of the shearing head 3. The second check pin 10 on the other hand is so arranged in the shearing head 3 and the fuse body 4 that it is immediately sheared, and thus releases the percussion pin 2, on loading of the shearing head 3 after the withdrawal of the first check pin 9. Due to the presence of the two check pins 9 and 10 it is thus possible to load the fuse as often as desired without operating the same in spite of the bayonet connection being in the "unsafe" position whilst after withdrawal of the first check pin 9 immediate shearing of the second check pin 10 and thus detonation of the fuse will be caused by loading of the fuse head 3.

To allow of the ready rotation of the fuse head 3 relatively to the fuse body 4, 5 for the purpose of bringing the bayonet connection to the "unsafe" position the first pin 9 acting merely as a check pin, is guided, as illustrated in Figs. 6 and 7, in a slot 16, of length corresponding to the angle of rotation, in the 55 percussion pin 2.

Furthermore in order to obtain the smallest possible length of fuse the end of the percussion pin towards the fuse cap 7 is constructed in the form of a hollow cylinder at the base of which the percussion point 8 is disposed. The support 6 for the fuse cap 7 projects into the hollow cylinder and consequently the fuse has a very inconsiderable height only amounting to about 36 mm. As a result the fuse is prevented from being unintentionally buckled and rendered inoperative by, say, being run over by vehicles or the like which may readily occur with long fuses due to the production of lateral forces.

As has already been mentioned above the fuse body consists of the two parts 4 and 5 screwed together. Consequently when the fuse is screwed by means of the thread 17 on the fuse cap support 6 into a mine or the like the part 4 together with the fuse head 3 may be screwed out of the part 5 subsequently. In this manner the fuse may be lengthened by, say, two-thirds of its normal length. It is thus readily possible to build up mines under bridges, railway tracks or other constructions without at first fitting fuses. The fuses may then be mounted subsequently when occasion demands and may be screwed up by relative rotation of the parts 4 and 5, until the fuse head 3 comes to bear on the construction in question.

Figs. 8-10 illustrate another modification of the fuse. This fuse operates in essentials precisely similarly to that described above and it differs only in that it has one safety device less; the bayonet connection safety device is omitted. In its stead the upper check pin 9 is made stronger and can only be drawn out to a certain predetermined limit, not in-

dicated in the drawing, from the shearing head 3 for the purpose of releasing the percussion pin 2. In contradistinction to the fuse illustrated in Figs. 1-7 therefore the check pin 9 cannot be entirely removed. The reasons for this are as follows: It may happen that the fuse is to remain for a long time in its mounted position and in an "unsafe" condition. Since the pin 9 cannot be wholly withdrawn the fuse is protected against the inward penetration of moisture and therefore against being spoiled from this cause. Furthermore the fuse may at any time also be rendered "safe" once more, say at night, in a simple manner. It is only necessary to press down somewhat the spring 18 which is arranged on the pin 9 and which has an angle shaped hook portion 19 adapted to rise out of the bore for the pin 9 to prevent unintentional setting of the fuse in the "safe" condition, and then to reinsert the pin 9 in the fuse head; the fuse is thereupon again in a "safe" condition for transport and may, if necessary, be used again at another point. The spring 18 is also intended to prevent unintentional falling out of the pin 9, setting the fuse in the "unsafe" condition, by its upwardly directed pressure on the percussion pin 2 in the inserted position of the pin 9. As contrasted with the first described fuse that illustrated in Figs. 8-10 has the advantage of being easier to handle. After the withdrawal of the check pin 9 the fuse is detonated either by withdrawal of the second check pin 10 from a distance or by shearing of said pin when the fuse head 3 is loaded.

What I claim is:—

1. In a fuse of the kind described, a cylindrical casing, a cap covering the upper end of said casing and having an outer skirt fitting on the exterior of said casing at said upper end, said casing having an internal flange at its upper end, a second skirt carried by said cap and fitting within said flange, a firing pin having a shank at its upper end fitting within the inner skirt and provided with an outwardly extending flange at its lower end, a compression spring between said flanges, a percussion cap support in said casing in normal spaced relation to said firing pin, and a removable safety and shear pin extending through both skirts, the upper part of the casing and said shank and arranged to hold the head of the cap slightly spaced above the casing when in firing position.

2. In a fuse of the kind described, a cylindrical casing, a cap covering the upper end of said casing and having an outer skirt fitting on the exterior of said casing at said upper end, said casing having an internal flange at its upper end, a second skirt carried by said cap and fitting within said flange, a firing pin having a shank at its upper end fitting within the inner skirt and provided with an outwardly extending flange at its

lower end, a compression spring between said flanges, a percussion cap support in said casing in normal spaced relation to said firing pin, and a removable safety and shear pin extending through both skirts, the upper part of the casing and said shank and arranged to hold the head of the cap slightly spaced above the casing when in firing position, said skirts being provided with circumferentially extending slots wherethrough said pin passes whereby the cap may be rotated on the casing, the slots in the outer casing each having a vertical upwardly extending portion at one end, said vertical portions being diametrically opposite each other, the slots in the inner skirt being of sufficient width to permit said head to seat on the casing upon the cap being rotated to bring the vertical extensions in alinement with said pin.

3. In a fuse of the kind described, a cylindrical casing, a cap covering the upper end of said casing and having an outer skirt fitting on the exterior of said casing at said upper end, said casing having an internal flange at its upper end, a second skirt carried by said cap and fitting within said flange, a firing pin having a shank at its upper end and fitting within said inner skirt, a spring urging said pin to firing position, a percussion cap support in said casing in normal spaced relation to said firing pin, a removable safety and shear pin extending through both skirts, the upper part of the casing and said shank and arranged to hold the head of the cap slightly spaced above the casing when in firing position, said skirts being provided with circumferentially extending slots wherethrough said pin passes whereby the cap may be rotated on the casing, the slots in the outer skirt each having a vertical upwardly extending portion at one end, said vertical portions being diametrically opposite each other, the slots in the inner skirt being of sufficient width to permit the head of the cap to seat on the casing upon the cap being rotated to bring the vertical extensions in alinement with said pin, the slots in the inner skirt each having a downwardly extending portion at one end opening through the bottom of the skirt, said downwardly extending portions being opposite the ends of the slots in the outer skirt which lie remote from the vertical extensions.

4. In a fuse of the kind described, a cylindrical casing, a cap covering the upper end of said casing and having an outer skirt fitting on the exterior of said casing at said upper end, said casing having an internal flange at its upper end, a second skirt carried by said cap and fitting within said flange, a firing pin having a shank at its upper end and fitting within said inner skirt, a spring urging said pin to firing position, a percussion cap support in said casing in normal

spaced relation to said firing pin, a removable safety and shear pin extending through both skirts, the upper part of the casing and said shank and arranged to hold the head of the cap slightly spaced above the casing when in firing position, said skirts being provided with circumferentially extending slots wherethrough said pin passes whereby the cap may be rotated on the casing, the slots in the outer skirt each having a vertical upwardly extending portion at one end, said vertical portions being diametrically opposite each other, the slots in the inner skirt being of sufficient width to permit the head of the cap to seat on the casing upon the cap being rotated to bring the vertical extensions in alinement with said pin, the slots in the inner skirt each having a downwardly extending portion at one end opening through the bottom of the skirt, said downwardly extending portions being opposite the ends of the slots in the outer skirt which lie remote from the vertical extensions, and a second safety pin passing through the slots in the inner skirt and the shank and positioned parallel to and immediately below the first safety pin, whereby the first safety pin may be withdrawn in safety position of the cap and the second safety pin will act to prevent movement of the firing pin relative to the cap.

In testimony whereof I have signed my name to this specification.

HANS GRUBER.
